[57] CLAIM

The ornamental design for a camping lantern reflector, as shown and described.

DESCRIPTION

FIG. 1 is a perspective view of the camper lantern reflector showing our new design;
FIG. 2 is a front elevational view thereof;
FIG. 3 is a rear end elevational view thereof;
FIG. 4 is a right side elevational view thereof, the left side elevational view being a mirror image of the view shown in this Figure;
FIG. 5 is a top plan view thereof; and,
FIG. 6 is a bottom plan view thereof.
